UNITED STATES PATENT OFFICE.

JULIUS PEGEL, OF PHILADELPHIA, PENNSYLVANIA, ASSIGNOR TO JOHN BROMLEY & SONS, OF SAME PLACE.

DESIGN FOR A RUG.

SPECIFICATION forming part of Design No. 19,391, dated October 29, 1889.

Application filed October 7, 1889. Serial No. 326,286. Term of patent 3½ years.

To all whom it may concern:

Be it known that I, JULIUS PEGEL, a subject of the Emperor of Germany, residing at Philadelphia, in the county of Philadelphia and State of Pennsylvania, have invented and produced a new and original Design for a Rug, of which the following is a specification, reference being had to the accompanying photographic print, forming a part thereof, which 5 conveys to any one skilled in the art of rug-weaving a clear understanding of the same, and is sufficient to enable such person to use my invention.

What I claim as my invention, and desire to secure by Letters Patent, is—

The design for a rug, consisting in the 15 ornamentalations shown in the photographic print accompanying this specification.

JULIUS PEGEL.
